UNITED STATES PATENT OFFICE.

CHRISTIAN PEDERSEN, OF ST. LOUIS, MISSOURI, ASSIGNOR TO LANDIS MACHINE COMPANY, OF ST. LOUIS, MISSOURI, A CORPORATION OF MISSOURI.

THREAD-LAYING MECHANISM FOR SEWING-MACHINES.

No. 872,744.

Specification of Letters Patent.

Patented Dec. 3, 1907.

Application filed March 7, 1907. Serial No. 361,090.

To all whom it may concern:

Be it known that I, CHRISTIAN PEDERSEN, a citizen of the United States, residing at St. Louis, Missouri, have invented a certain new and useful Improvement in Thread-Laying Mechanism for Sewing-Machines, of which the following is a full, clear, and exact description, such as will enable others skilled in the art to which it appertains to make and use the same, reference being had to the accompanying drawings, forming part of this specification, in which—

Figure 1 is a side elevation partly in section of a sewing machine provided with a thread-laying mechanism embodying the features of my invention; Fig. 2 is a top plan view showing the thread-laying mechanism and taken on a line just below the work-table; and Figs. 3 to 6 inclusive are detail views illustrating the various positions which the thread-carrying member and its co-operating member occupy in the operation of laying the thread in the barb of the needle.

This invention relates to sewing machines and particularly to that type which employ a barbed needle, such for example, as the sewing machines that are used in the manufacture of boots and shoes.

One object of my invention is to provide a thread-laying mechanism of simple construction that will not fail to lay the thread in the barb of the needle at each operation of the machine.

Another object of my invention is to provide a thread laying mechanism that will permit the under-thread to extend in a straight line from the work to the take-up during the operation of setting the stitch.

I have herein illustrated my improved thread-laying mechanism in combination with a sewing machine that is provided with a curved barbed needle that passes downwardly through the work to engage the underneath thread and then moves upwardly to pull said underneath thread up through the work. It should be understood, however, that the thread-laying mechanism herein shown is not limited in its use to this particular type of machine as it could be used with any machine provided with a barbed needle.

Referring to the drawings which represent the preferred form of my invention, I designates a curved needle that is adapted to pass downwardly through the work to permit the

under thread 2 to be placed in the barb or hook 3 thereon, the machine being provided with suitable mechanism, not shown, for actuating said needle.

My improved thread-laying mechanism 60 consists of a thread-carrying member A through which the under thread 2 passes and a member B that co-operates therewith in the operation of laying the thread in the barb of the needle. The thread-carrying member, 65 as shown in Fig. 1, is provided with a shank 4 which extends through the sleeve 5 of a pinion or gear 6 and with a perforated head 7 arranged out of alignment with said shank, the under thread 2 passing through said perforated head. A nut 8 that is threaded on the lower end of the shank 4 securely clamps said member to the sleeve of the pinion 6 so that whenever the pinion is moved the thread-carrying member A will move therewith. The sleeve of the pinion 6 is journaled in a stationary support 9 underneath the work-table 10, said sleeve being arranged slightly to one side of the path of movement of the needle 1, as shown in Figs. 3, 4 and 5; 70 the shank 4 of the thread-carrying member which extends through said sleeve being shown in dotted lines in these figures. As the perforated head 7 of the thread-carrying member is located at one side of the vertical axis of said member, said head will travel in a circular path around the needle when it is in its lowermost position, as shown in Fig. 1, and thus lay the thread in the barb of the needle, as hereinafter more fully described. 75 The means for actuating the thread-carrying member A consists of a lever 11 pivotally connected to the underneath side of the support 9 and provided at its outer end with a rack segment 12 that co-operates with the pinion 6, the inner end of said lever having a link 13 connected thereto which is secured to the upper end of a rock arm 14. This rock arm is fulcrumed in a stationary support 15 and is provided with a roll 16 that travels in a cam 80 groove 17 formed in the periphery of a cam block 18 on the main shaft 19 of the machine.

The member B that co-operates with the thread-carrying member is pivoted at 20 to the underneath side of the work-table 10 and 85 is provided with a hook or finger 21, as shown in Figs. 2 to 6, inclusive, said member also having an elongated slot 22 that receives a pin 23 at the outer end of a reciprocating bar 24. The bar 24 is mounted in a guideway 25 90

on the frame of the machine and the rear end of said bar is pivotally connected to the upper end of a rock arm 26 provided with a roll 27 that travels in a cam groove 28 formed in 5 the side face of the cam block 18.

Fig. 3 shows the thread-carrying member A and the member B that coöperates therewith at rest in the positions they occupy after the needle 1 has passed through the 10 work and has reached the limit of its downward movement, as shown in Fig. 1. The thread-carrying member first moves from the position shown in full lines in Fig. 3 to the position shown in broken lines in said figure 15 so as to carry the under thread into the path of movement of the hook on the member B. The member B then moves into the position shown in Fig. 4 and in so doing engages that portion of the thread which extends between 20 the underneath side of the stock and the head 7 of the thread-carrying member, the movement of the member B operating to draw some of the under thread from the spool or source of supply. The member B 25 remains in the position to which it has been moved and the thread-carrying member then rotates in the reverse direction to that in which it previously moved, thereby carrying the portion of the thread arranged on the 30 underneath side of the hook or finger 21 around the shank of the needle and into the position shown in Fig. 5. The needle then moves upwardly through the work, its barb engaging the thread, and the member B returns quickly to its original position shown 35 in Fig. 3, the thread-carrying member also starting to return to its original position but coming to rest when the perforation in its head 7 is in alinement with the opening that 40 the needle formed in the work. The thread-carrying member remains in this position, as shown in Fig. 6, while the take-up 30 is operating to set the stitch and as the guide through which the thread passes; namely, 45 the perforation in the head 7, is in alinement with the needle-hole in the work, the thread will extend in a straight line from the work to the roll 31 on the take-up, thereby enabling the take-up to exert a direct downward pull 50 on the thread in a straight line and thus not subject the thread to any undue strain. After the stitch has been set the thread-carrying member A returns to its normal position,

as shown in Fig. 3, the member B having returned to its normal position, as previously 55 described.

I will not describe the exact form of the cam grooves which impart movement to the rock arms 14 and 26 as it will, of course, be understood that these cams are so laid out 60 that the members A and B will move in the manner previously described.

Having thus described my invention, what I claim as new and desire to secure by Letters Patent is:

1. In a thread-laying mechanism for sewing machines, a rotatable thread-carrying member having a pinion secured thereto, a lever having a toothed segment meshing with said pinion, a positively actuated rock arm, 70 a link connecting said rock-arm and lever together, an oscillating thread-engaging member having an elongated slot formed therein, a reciprocating bar provided with a pin which enters said slot, and a positively actuated rock arm connected to the rear end of 75 said reciprocating bar; substantially as described.

2. In a thread-laying mechanism for sewing machines, a work support; an oscillating 80 thread-engaging member located beneath said support and having a laterally projecting finger, a rotatable thread-laying member arranged underneath the thread-engaging member and consisting of a shank having a 85 head provided with a thread-receiving opening located at one side of said shank, means for rotating said thread-laying member first in one direction to carry the thread into the path of movement of the laterally projecting 90 finger of the thread-engaging member and thereafter in a reverse direction to cause it to travel around the needle, and means for actuating the thread-engaging member to cause it to hold the thread while the thread-laying member is traveling around the needle and thereafter release the thread and return quickly to normal position; substantially 95 as described.

In testimony whereof I hereunto affix my 100 signature in the presence of two witnesses, this fifth day of March 1907.

CHRISTIAN PEDERSEN.
